DAMPER

John L. Harris, Minneapolis, Minn., assignor to
Minneapolis-Honeywell Regulator Company,
Minneapolis, Minn., a corporation of Delaware

Application March 29, 1940, Serial No. 326,687

5 Claims. (Cl. 98—110)

This invention relates to dampers of the co-operating louver type and particularly to the type of such damper in which adjacent louvers rotate in relatively opposite angular directions during any particular operation whether opening or closing.

Such dampers are now well known in the art and have the advantage over the conventional damper in which adjacent blades remain parallel of providing a smoother flow of air through the damper at the smaller openings. In order to provide a tight shut-off in closed position it is desirable that adjacent damper blades overlap and the problem is introduced of opening the louvers in such a way that there will be no interference between adjacent louvers as they are moved from closed position. To accomplish this the louver which overlaps must move faster initially than the overlapped louver.

It is an object of the present invention to provide a simple mechanism by means of which oppositely rotating overlapping louvers will be so moved from closed position that the overlapping louver will lead the overlapped louver.

A further object is to provide such a mechanism that will additionally move all the louvers into parallel relation at full open damper position.

Other objects will be apparent from the drawing, specification, and claims.

In the drawing:

Figure 1 shows a damper incorporating the invention in closed position.

Figure 2 shows the same damper in full open position.

The damper shown in Figures 1 and 2 comprises a frame 6 which is of the conventional type and generally rectangular in form. Shafts 8, 10, 12, and 14 are journalled in the damper frame and are secured to the louvers 9, 11, 13, and 15, respectively. A rod 18 is pivoted to the louvers 9 and 13 and cause these two louvers to remain parallel. Likewise a rod 20 is pivoted to louvers 11 and 15 to cause these louvers to move together. Thus it will be seen that louvers 9 and 13 remain parallel and louvers 11 and 15 remain parallel. Angle brackets 23 are suitably secured to the top and bottom edges of the frame and serve as seals between louvers 9 and 15 and the frame 6 when the louvers are in closed position.

In order that alternate damper blades may be caused to move in reverse angular directions during both opening and closing movements of the damper, a mechanism is utilized which will now be described. Suitably pivoted at 24 in the frame 6 between the pivots 8 and 10 for the louvers 9 and 11 is a bell crank member 25. The louver 9 is provided with a bracket 26 between the pivot 8 and lower edge of the louver while the louver 11 is provided with a bracket 28 at a point below its

pivot 10. A link 30 is attached to louver 9 at the bracket 26 and is attached to the bell crank member 25 at a pivot 31. The lower side of bell crank member 25 is attached at 33 to a link 35 which is connected to the bracket 28 of louver 11.

As shown in Figure 1 of the drawing the louver 11 is shaped at its upper edge to overlap the louver 9 and to form a suitable seal therewith when in the closed position. Likewise the louver 13 overlaps the louver 11 and the louver 15 overlaps the louver 13. It will be understood that when the damper is opened from the position shown in Figure 1, the louvers 9 and 13 will move in a clockwise direction while the louvers 11 and 15 move in a counter-clockwise direction. It will also be apparent that the louvers 11 and 15 must move a greater distance initially from closed position than the louvers 9 and 13 in order that the adjacent edges may disengage as the damper opens. The links 30 and 35 together with the bell crank member 25 are so arranged that this may be accomplished. The instantaneous speeds of the louvers as they start to move from closed position will depend on the ratios between the perpendicular distances from the associated links 30 and 35 to the centers of the damper pivots and to the center of the bell crank pivot. As seen in Figure 1 the perpendicular distance from the louver pivot 8 to the projection of a line connecting the pivots 26 and 31 of the link 30 is designated as a , while the perpendicular distance from the center line of the link 35 to the pivot 10 of louver 11 is designated as a' . The perpendicular distance from the center line of link 30 to the pivot 24 of the bell crank member 25 is indicated as b while the perpendicular distance from the projection of the center line of the link 35 to the pivot 24 for the bell crank member 25 is designated as b' . The relation between the initial angular speeds of the louvers 9 and 11 as they move from the position shown in Figure 1 may therefore be designated as

$$\text{Speed}_9 = \text{Speed}_{11} \times \frac{a'}{b'} \times \frac{b}{a}$$

In the present showing, the distances a and a' have been made equal and therefore the ratio of initial speeds of damper blades 9 and 11 may be given as

$$\text{Speed}_9 = \text{Speed}_{11} \times \frac{b}{b'}$$

It will be seen therefore that since the perpendicular distance b' between the center line of the link 35 and the pivot for the bell crank member 25 is greater than the perpendicular distance b between center line of the link 30 and the pivot 24 for the bell crank member 25, the louver 11 will lead louver 9 in initial opening movement and therefore their overlapping edges will clear. The

relation of the parts is also such that the louvers will be parallel in full open position of the damper as shown in Figure 2. Since alternate louvers of the damper as a whole are connected to louvers 9 and 11 to move therewith all of the louvers will operate similarly to louvers 9 and 11.

It will be understood that any suitable damper motor may be connected to the damper mechanism in the usual manner so that it may be automatically controlled.

It will therefore be seen that I have provided a simple mechanism for operating a damper in which alternate louvers overlap and are so connected as to move in opposite angular directions.

I claim as my invention:

1. In a damper mechanism in which alternate louvers are adapted to rotate in relatively opposite angular directions, in combination, a frame, a first louver pivoted in said frame, a second louver an edge of which overlaps said first louver when the damper is in closed position also pivoted in said frame, a member pivoted in said frame between the pivots for said first and second louvers, the pivot for said member being parallel to the pivots for said louvers, a first link pivoted to said first louver at a point between the pivots for said louver and said member and to said member, a second link pivoted to said second louver on the side of the louver pivot away from the pivot for said member and to said member, the proportions of the parts being such that in closed damper position the perpendicular distance from said second link to the pivot for said member is greater than the perpendicular distance from said first link to the pivot for said member.

2. In a damper mechanism in which alternate louvers are adapted to rotate in relatively opposite angular directions, in combination, a frame, a first louver pivoted in said frame, a second louver an edge of which overlaps said first louver when the damper is in closed position also pivoted in said frame, a member pivoted in said frame between the pivots for said first and second louvers, the pivot for said member being parallel to the pivots for said louvers, a first link pivoted to said first louver at a point between the pivots for said louver and said member and to said member, a second link pivoted to said second louver on the side of the louver pivot away from the pivot for said member and to said member at such a point that at closed damper position the perpendicular distance from said second link to the pivot for said member is greater than the perpendicular distance from said first link to the pivot for said member.

3. In a damper mechanism in which alternate louvers are adapted to rotate in relatively opposite angular directions, in combination, a frame, a first louver pivoted in said frame, a second louver an edge of which overlaps said first louver when the damper is in closed position also pivoted in said frame, a bell-crank pivoted in said

frame between the pivots for said louvers, the pivot for said bell-crank being parallel to the pivots for said louvers, a first link pivoted to said first louver at a point between the pivots for said louver and said bell-crank and to one arm of said bell-crank, a second link pivoted to said second louver on the side of the louver pivot away from the pivot for said bell-crank and to the other arm of said bell-crank at such a point that at closed damper position the perpendicular distance from said second link to the pivot for said bell-crank is greater than the perpendicular distance from said first link to the pivot for said bell-crank.

4. In a damper mechanism in which alternate louvers are adapted to rotate in relatively opposite angular directions, in combination, a frame, a first louver pivoted in said frame, a second louver an edge of which overlaps said first louver when the damper is in closed position also pivoted in said frame, a member pivoted in said frame between the pivots for said first and second louvers, the pivot for said member being parallel to the pivots for said louvers and substantially in the plane of the pivots for said louvers, a first link pivoted to said first louver at a point between the pivots for said louver and said member and to said member, a second link pivoted to said second louver on the side of the louver pivot away from the pivot for said member and to said member, the proportions of the parts being such that in closed damper position the perpendicular distance from said second link to the pivot for said member is greater than the perpendicular distance from said first link to the pivot for said member.

5. In a damper mechanism in which alternate louvers are adapted to rotate in relatively opposite angular directions, in combination, a frame, a first louver pivoted to said frame, a second louver overlapping an edge of said first louver when the damper is in a closed position, and leading said edge of said first louver in an initial opening movement, a member pivoted to said frame between the pivots for said louvers on an axis parallel to the axis of the pivots of said louvers, a first link pivoted to said first louver on the side of the pivot of said first louver toward the pivot of said second louver, and to said member, a second link pivoted to said second louver on the side of the pivot of said second louver away from the pivot of said first louver, and to said member, the ratio of the perpendicular distance between said second link and the axis of said member to the perpendicular distance between said second link and the axis of said second louver being greater than the ratio of the perpendicular distance between said first link and the axis of said member to the perpendicular distance between said first link and the axis of said first louver, when the damper is in closed position.

JOHN L. HARRIS.
